UNITED STATES PATENT OFFICE

ERNEST O. FREDERICS, OF NEW YORK, N. Y., ASSIGNOR TO E. FREDERICS, INC., OF NEW YORK, N. Y., A CORPORATION OF NEW YORK

PORTABLE SUSPENSION DEVICE

Application filed March 25, 1926. Serial No. 97,365.

This invention relates to a conductor housing apparatus of improved construction. It is an object of the invention to provide a housing capable of use in numerous different associations, but particularly adapted to be employed in the practice of hair-waving methods, and the parts of which apparatus will be relatively simple and few in number and will be capable of ready assemblage, aside from the fact that it may be utilized over long periods of time with freedom from mechanical difficulty.

It is a further object of the invention to construct an article of the nature stated which may be readily placed in operative association with a source of electrical energy or disconnected therefrom, and which will be light and readily handled by an operator.

Other objects of the invention will in part be obvious and will in part appear herein-after.

The invention accordingly comprises the features of construction, combination of elements and arrangement of parts which will be exemplified in the construction hereinafter set forth, and the scope of the application of which will be indicated in the claims.

For a fuller understanding of the nature and objects of the invention reference should be had to the following detailed description taken in connection with the accompanying drawings, in which:

Figure 1 is a side elevation of one form of apparatus embodying the improved construction of the present invention and showing the same in applied position;

Fig. 2 is a sectional end view thereof; and

Fig. 3 is a sectional side view taken along the lines 3—3 and in the direction of the arrows in Fig. 2, certain of the parts being broken away to disclose the underlying construction.

In these several views the numeral 5 indicates the housing proper, which consists of a pair of complementary sections each preferably providing a reduced lower portion and an enlarged head. The parts of the housing are secured together in any desirable manner, and within this housing is a pair of drums 6 rotatably mounted upon stub-shafts

7. The periphery of these drums is recessed as at 8 so as to provide a retaining groove for electrical conductors 9. Springs 10 cooperate one with each of the drums and tend to rotate the same in such a direction that the cables or conductors are retracted to a maximum extent within the housing, and the major portion thereof is coiled around the drums.

The bodies of the cables pass over pulleys 11 rotatably mounted upon stub-shafts 12 associated with the housing, these pulleys being grooved to guide the cable, and the housing being slotted as at 13 adjacent the pulleys in order to permit of the passage of the cable to points beyond the housing. Suitable checking devices, as, for example, balls 14, may cooperate with the pulleys 11 in order to prevent an accidental retraction of the cables, it being understood that an operator by a suitable actuation of the parts may release the lock thus provided to allow the cable to assume its retracted position. As aforesighted, this device is primarily intended for use in connection with permanent hair-waving, and to this end it will be seen that in the illustrated embodiment appropriate forms of heaters 15 have been shown in association with the cable ends. It will be understood, however, that, if desired, any suitable form of appliances might be provided in lieu of these heaters.

Each of the drums preferably carries a pair of contact rings 16 upon its outer face, and the ends of each of the cables carried by the drums are connected to the rings. In the present instance, each of the housing sections or parts has a casing 17 secured to and spaced from its outer face, these casings serving to conceal and enclose the ends of the shafts upon which the drums are mounted, and also providing conduits extending to a point adjacent the lower end of the housing. Mounted within each of these conduits are pairs of holders 18 for spring-pressed brushes 19, these holders being arranged in line with the rings 16 and the brushes consequently bearing against these rings. Extending within the conduits provided by the casing 17 and electrically connected with the brushes are

pairs of wires 20, the lower ends of which are connected to plug pins 21 extending from the lower end of the housing.

As a consequence, it will be appreciated that if a support is provided for this housing and embodies a pair of electrically charged contact portions 22, to which access may be had through openings, an operator, by simply inserting the pins of the plug portions 21

10 through these openings, will secure the housing in position, and will furthermore place the cables 9 in electrical connection with the source of energy. Furthermore, during the retracting and projecting of these cables the 15 brushes will at all times maintain this electrical connection, and it will be unnecessary to provide wires coiled contra to the cables upon the drums in order to maintain the same.

20 Finally, it will be understood that the housing and associated parts may be made of any desirable material and may be constructed severally, as shown, or otherwise, as is most convenient. To this end, it is preferred that molded bakelite be employed in the 25 construction of the housing parts and such other mechanism as may seem most desirable.

Thus, among others, the objects of this invention have been accomplished, and since 30 certain changes may be made in the above construction, and different embodiments of the invention could be made without departing from the scope thereof, it is intended that all matter contained in the above description or 35 shown in the accompanying drawings shall be interpreted as illustrated and not in a limiting sense.

It is also to be understood that the following claims are intended to cover all of the 40 generic and specific features of the invention herein described and all statements of the scope of the invention which as a matter of language might be said to fall therebetween.

Having described my invention, what I 45 claim as new and desire to secure by Letters Patent is:

1. The herein-described portable suspension-device comprising, in combination, a housing, a drum mounted revolubly on a shaft 50 within said housing, a pair of annular conducting-plates carried by said drum and concentric with said shaft, a pair of contact-brushes mounted on the wall of said housing and projecting inwardly and into contact respectively with said annular plates, a flexible conductor consisting of two wires which are respectively connected electrically with said annular plates, said flexible conductor being coiled about said drum and extending out 55 through an opening in the wall of said housing, a coiled spring secured at one end to said drum and at the other end to said shaft, whereby pulling out said flexible conductor winds up said spring and puts it under tension which will retract said conductor when

released, wires leading respectively from said brushes to pin-plug contact-members that project from said housing for insertion at will into suitable contact-sockets, a shield-plate carried by said housing and coacting with the latter in providing a conduit for said last-named wires, and a checking-means automatically preventing automatic retraction of the flexible conductor.

2. In a portable suspension-device such as called for by the preceding claim, said checking-means comprising a pulley mounted within the housing of the device, and engaged by the flexible conductor of said device, which pulley is arranged to be given rotary movement by the longitudinal movement of said flexible conductor, and a ball located in a seat in said housing and operating by gravity to engage said pulley and prevent automatic retraction of said flexible conductor.

3. The herein-described portable suspension-device comprising, in combination, a housing, a spring-actuated drum mounted revolubly within said housing, a flexible conductor consisting of two wires which are respectively in constant electrical connection with a source of current, said conductor being coiled about said drum and extending out through an opening in the wall of said housing and carrying at its outer end an electric device, a pulley mounted revolubly within said housing and in contact with said conductor between said opening and said drum, and a ball located within a seat in said housing and operating by gravity to engage said pulley and thereby prevent automatic retraction of said conductor.

In testimony whereof I affix my signature.

ERNEST O. FREDERICKS.
